UNITED STATES PATENT OFFICE

LEO W. KENNEDY, OF DETROIT, MICHIGAN

CLIP CONSTRUCTION

Application filed October 2, 1929. Serial No. 396,852.

This invention relates to show cases, and more particularly to an improved clip construction for uniting the top, front and end or transverse lights at the juncture thereof.

The invention has as one of its important objects to provide a clip construction of this nature which may be cheaply and economically manufactured, and which will present a slightly appearance in the completed structure.

Another object of the invention is to provide a clip construction wherein swivel or pivotal movement is permitted between the several light engaging members, whereupon the connecting member will adjust itself to varying conditions of relative angular displacement between the several lights without breakage or other injury thereto.

This invention constitutes a division in part of my co-pending application, Serial Number 269,806.

The several objects, advantages and novel details of construction of the invention will be made more apparent as this description proceeds, especially when considered in connection with the accompanying drawings wherein:

Figure 1 is a transverse sectional view through a show case with my invention applied thereto;

Figure 2 is a fragmentary perspective view of the juncture of the top, front and end lights of a show case showing the application of my improved clip;

Figure 3 is a perspective view of the clip detached;

Figure 4 is a top plan of the structure illustrated in Figure 2;

Figure 5 is a side elevation of the structure illustrated in Figure 2; and

Figure 6 is a front elevation of the structure illustrated in Figure 2.

Referring now particularly to the drawings wherein like reference characters indicate like parts, it will be noted there is illustrated in Figure 1 a substantially conventional form of show case comprising a base or bottom 10 which in practice is adapted to rest upon the framework of the counter or the like upon which the show case is supported. Ar-

ranged substantially peripherally of the base 10 are fillet or moulding strips 11 which receive and support the lower edges of the glass sheets or lights constituting the ends and front of the show case. The reference character 12 indicates the front light, 13 the top light and 14 the transverse or end lights. The reference character 15 indicates the open rear side of the show case, and 16 the door for closing this open side. The reference character 17 indicates a longitudinally extending frame member of the show case.

The present invention relates more particularly to a clip or connecting member for uniting, for instance, the front, top and end or transverse lights at the juncture thereof, and by reference to Figures 2 to 6 inclusive the construction of my improved clip will be made more apparent.

This clip comprises a substantially flat member 18 which may be conveniently formed of sheet metal, one end of which is bent upwardly as at 19, and backwardly as at 20 substantially parallel to the portion 18. This constitutes a return-bent portion 21 adapted to embrace and engage the forward edge of the top light 13 as most clearly illustrated in Figures 2, 4 and 5. The main body portion 18 of the clip is adapted to lie under the top light 13 and between the top light and the adjacent upper edges of the front and end lights 12 and 14.

Pivoted to one end of the clip member 18, as at 22, is a substantially U-shaped member 23 also preferably formed of sheet metal. This member 23 is adapted to embrace and engage the upper edge of the end or transverse light 14.

Pivoted to the member 18, intermediate the return-bent portion 21 and the U-shaped member 23, is a second substantially U-shaped member 24 pivotally connected to the member 18 as at 25. This U-shaped member is adapted to embrace and engage the adjacent upper edge of the front light 12.

The forward edge of the end or transverse light 14 is preferably cut away or recessed as at 26 to accommodate the thickness of the adjacent portion of the member 24, and the upper edge of this end light is recessed as at 27.

to accommodate the U-shaped member 23 and is cut away further as at 28 to accommodate the thickness of the main member 18. Felt 29 is preferably arranged between the clip and 5 the top light, as most clearly illustrated in Figure 5.

As seen most clearly from Figure 6, the upper edge portion of the front light 12 is recessed adjacent the edge thereof as indicated at 30, to receive the U-shaped member 24.

The member 18 has a downwardly bent tongue 31 apertured as at 32 to receive a tie rod 33. The other end of this rod is connected as at 34 to the frame member 17. The end of the rod passing through the aperture 32 is threaded to receive nuts 35 by means of which the tension on the tie rod may be adjusted.

20 In constructing the clip the tongue portion 31 may be conveniently formed by longitudinally slitting the clip body 18 and bending one portion thereof downwardly, the other portion being employed for pivotally 25 mounting the U-shaped member 23.

It will be noted that both of the members 23 and 24 are substantially U-shaped so that they may embrace the adjacent edges of the lights but will permit limited relative longitudinal sliding movement of the lights there- 30 through. Moreover by pivotally securing the U-shaped members 23 and 24 to the clip body 18 slight relative angular displacement, due to weaving of the show case, is permitted 35 between the front, top and end lights without liability of fracture or other injury to the lights. The recessed or cut away portions 26, 28 and 30 compensate for the thickness of the adjacent portions of the clip to thus permit the several lights to be brought 40 into more or less intimate contact one with the other, whereas the recess 27, in which the member 23 rests, prevents any relative sliding movement of the clip which would 45 permit a dis-engagement or objectionable separation of the lights.

50 Reservation is made to make such changes in the non-essential details of construction herein illustrated as may come within the purview of the accompanying claims.

55 What I claim as my invention is:

1. In a show case, the combination with 60 front, side and top lights thereof, of a connecting member for said lights comprising a member provided with a return-bent end 55 portion for embracing the edge of the top light, a U-shaped member rotatively connected thereto for embracing the edge of the side light, and a U-shaped clip member rotatively secured to said member and engage- 65 able with the edge of the front light.

2. In a show case construction, the com- 65 bination with top, end and front lights, of a clip at the juncture thereof comprising a member extending beneath said top light and having a return-bent end portion engaging

said top light, and substantially U-shaped members independently pivotally connected to said first member and engaging the edges of said end and front lights.

3. In a show case construction, the com- 70 bination with top, end and front lights, of a connecting member therefore comprising a flat sheet metal member extending between said top light and the adjacent upper edges 75 of said end and front lights and having a return-bent end engaging the edge of said top light, a U-shaped member pivotally connected to the underside of said flat member and engaging the adjacent edge of said front light and a U-shaped member pivotally connected 80 to said flat member spaced from said first U-shaped member for engaging the adjacent edge of the end light.

4. In a show case construction, the com- 85 bination with top, end and front lights, of a clip at the juncture thereof comprising a member extending beneath said top light and having a return-bent end portion engaging 90 said top light, and a pair of substantially U-shaped members independently connected to said first member and engaging the edges 95 of said end and front lights respectively, one of said U-shaped members being pivotally connected to said first member, for the purpose set forth.

In testimony whereof I affix my signature.
LEO W. KENNEDY.
